UNITED STATES PATENT OFFICE.

LEROY G. ZIMMERMANN, OF MILWAUKEE, WISCONSIN.

STORM-WATER INLET.

Application filed April 2, 1928. Serial No. 266,513.

This invention relates to improvements in storm water inlets.

It is the object of this invention to provide a novel and improved form of storm water inlet adapted for manufacturing methods in production quantities, the device having a substantially universal application to fit varying conditions of installation and thereby by being adapted to eliminate to a large degree the hand labor heretofore required in such installations.

In the drawings:

Figure 1 is an axial section of a device embodying this invention.

Figure 2 is a plan view thereof.

Like parts are identified by the same reference characters throughout the several views.

In accordance with this invention the inlet is made in the form of a basin which may be cast of iron or other metal in the shape indicated at 5. It is important to note that the basin is so designed as to have a considerable water capacity without any abrupt curves, recesses or sharp angles in which sand or other foreign matter may lodge. The necessity of cleaning individual storm water inlets is thereby eliminated and the cast construction also eliminates the hand work heretofore necessary in building inlets of ma-

sonry.

The basin shaped receptacle 5 is provided with a broad flange at 6 upon which two courses of brick may be laid at 7 as shimming for the standard storm inlet frame 8 and slide inlet box 9. These parts correspond to general practice and are not necessary to this invention in the identical form in which they are shown.

The primary reason why devices of this kind have heretofore been built of brick and built to such considerable depths as to provide objectionable settling pools has been the supposed necessity for going below the frost line so that heaving of the basin would not disrupt connections to the drain. This difficulty is eliminated in the present device and

at the same time universality of installation is secured by the provision of a special elbow at 10 which has a very broad and unusually deep bell shaped top 11 into which is loosely fitted the reduced neck portion 12 of the basin 5. Obviously the elbow may be turned to any angle whatsoever with reference to the basin about the discharge neck 12 as an axis and the drain may thus lead in any direction from the point of installation. The elbow 10 may be loosely fitted into a standard drain tile 15 as illustrated, the drain tile being provided with a proper pitch toward the storm sewer.

The loose connection between the elbow fitting 10 and the collecting basin 5 permits these parts to retain engagement for the operative discharge of water irrespective of relative vertical movement. In other words frost acting to heave the ground upwardly against flange 6 of the basin may elevate the basin considerably above its normal position in elbow 10 but the length of flange 11 and neck 12 is such that an operative communication and registry of the parts will nevertheless be maintained. It is even possible for elbow 10 to be heaved by frost without losing its operative engagement either with the basin or the tile. Contrary to the usual practice, no cement is used in these joints, the length of the joint and its loose fit being depended upon to permit relative movement while maintaining engagement.

I claim:

A storm water inlet comprising a cast-iron basin tapering from top to bottom and provided with a discharge neck at its bottom and a substantially horizontal integral flange at its top, an inlet frame mounted upon said flange together with an elbow fitting provided with a relatively large bell loosely engaged in registry about said neck and adjustable thereon to any desired angle, and a drain tile loosely engaged with the outlet of said elbow fitting.
